P. F. MURPHY,
CYANID GAS FUMIGATING APPARATUS.
APPLICATION FILED APR. 27, 1916.

1,216,593.

Patented Feb. 20, 1917.

Inventor
Peter Francis Murphy,

By C. L. Parker.

Attorney

UNITED STATES PATENT OFFICE.

PETER FRANCIS MURPHY, OF NEW ORLEANS, LOUISIANA.

CYANID-GAS FUMIGATING APPARATUS.

1,216,593.

Specification of Letters Patent. Patented Feb. 20, 1917.

Application filed April 27, 1916. Serial No. 93,908.

To all whom it may concern:

Be it known that I, PETER FRANCIS MURPHY, M. D., a citizen of the United States, residing at New Orleans, in the parish of Orleans and State of Louisiana, have invented certain new and useful Improvements in Cyanid-Gas Fumigating Apparatus, of which the following is a specification.

- This invention relates to an improvement 10 in cyanid gas fumigating apparatus, and has particular reference to such a device whereby fumigation may be conveniently and expeditiously carried on, with the minimum danger.
- 15 An important object of the invention is to provide a device of the above mentioned character, whereby the different chemicals employed in the preparation of the fumigating gas are completely confined during the 20 generation of the gas, thereby reducing the danger, usually incurred by a person in preparing the gas, and such device being at all times under the complete control of the operator.
- 25 Other objects and advantages of the invention will be apparent during the course of the following description.

In the accompanying drawings forming a part of this specification, and in which like numerals designate like parts throughout the same,

Figure 1 is a side elevation of a device embodying my invention,

Fig. 2 is a vertical section taken on line 35 2—2 of Fig. 1, and,

Fig. 3 is a transverse section taken on line 3—3 of Fig. 1.

Referring to the drawings, wherein is shown a preferred embodiment of my invention, the numeral 5 designates a mixing chamber. The upper end or top of this mixing chamber is provided with a relatively large preferably circular opening 6, through which sulfuric acid is admitted to the mixing chamber. Bolted or otherwise securely fastened to the top of the mixing chamber 5 and surrounding the opening 6 is a ring 7, provided with interior screw-threads, for a purpose to be described. Packing 8 is interposed between the top of the chamber and the ring 7, to insure an air-tight joint there-between.

Screw-threaded within the ring 7 is a nip-

ple or filling tube 9. This filling tube is screw-threaded at its upper end and receives thereon a detachable cap 10. This cap 10 has handles 11, for the purpose of rotating the same upon the tube 9. The cap 10 is provided centrally thereof with an opening 12, receiving a take-off pipe 13. Any suitable union may be had between the pipe 13 and the cap 10, as is obvious.

Located within and near the lower end of the tube 9 is a butter-fly or disk valve 15, of substantially the same diameter as the tube 9. This butter-fly valve is securely fixed to a rock-shaft 16, journaled through bearings 17, preferably formed integral with the tube 9. These bearings 17 are in the form of stuffing boxes and insure an air-tight joint. At one of its outer ends, the shaft 16 is bent at a right angle, to provide a crank 18, for the purpose of rotating the butter-fly valve. A latch or hook 19 is pivoted to the side of the tube 9, as shown at 20, and is adapted to engage the crank 18 when in the vertical position, to prevent undue movement. A similar latch 21 is pivoted, as shown at 22, upon the top of the tank 5, to engage and hold the crank 18, when in the horizontal position.

A take-off pipe 23 is located adjacent the bottom of the tank 5, for the purpose of draining the same. This take-off pipe is provided with a cut-off valve 24.

In the use of the apparatus, when it is desired to form a gas for the purpose of fumigating, the cap 10 is removed. The butter-fly valve is then turned to the vertical position, as shown in Fig. 2, and sulfuric acid is poured through the tube 9 into the mixing chamber 5, to the desired depth. The butter-fly valve is then turned to the closed position, thereby cutting off communication between the mixing chamber 5 and the tube 9. Sodium cyanid is then placed upon the butter-fly valve 15 and the cap 10 is again replaced upon the tube 9. The valve 15 is then turned to allow the sodium cyanid to fall within the chamber 5 and thereby mix with the sulfuric acid, the same forming a hydrocyanic acid gas. As the gas forms, it is taken off through the take-off pipe 13, to the place desired to be fumigated.

It is to be understood that the form of my invention herewith shown and described is to be taken as a preferred example of the

same, and that various changes in the shape, size, and arrangement of parts may be resorted to without departing from the spirit of my invention or the scope of the subjoined claims.

Having thus described my invention, I claim:

1. In gas generating apparatus, a mixing chamber provided in its top with an opening, a tube connected with the upper end of the mixing chamber and arranged in proximity to the opening, means located within the lower end of said tube to cover and uncover the opening, and a removable cap carried by the upper end of the tube.
2. In gas generating apparatus, a mixing chamber, an opening formed within its upper end, a ring carried by the upper end of the mixing chamber and surrounding the opening, a tube connected with said ring, a butter-fly valve located within said tube and adapted to completely close the same, a crank carried by the butter-fly valve, a latch to hold the crank in the vertical position, a latch to hold the crank in the horizontal position, a detachable cap having screw-thread-

ed engagement with the tube, and a take-off pipe carried by the cap.

3. In gas generating apparatus, a mixing chamber, a drain pipe connected with the lower end of said chamber, an opening formed in the upper end of the mixing chamber, a ring secured to the top of the mixing chamber and completely surrounding the opening, packing arranged between the ring and the top of the mixing chamber, a tube located above the mixing chamber and having screw-threaded engagement within the ring, a transverse shaft arranged near the lower end of the tube, stuffing boxes receiving the shaft, a butter-fly valve carried by the shaft, a crank formed upon one end of the shaft to turn the butter-fly valve, means to hold the crank against improper movement, a cap having screw-threaded engagement with the upper end of the tube, and a take-off pipe carried by the cap.
